ROBERT MIEHLE, OF CHICAGO, ILLINOIS, ASSIGNOR TO CONTINENTAL & COMMERCIAL TRUST & SAVINGS BANK, TRUSTEE, OF CHICAGO, ILLINOIS.

RECIPROCATING-BED-DRIVING MECHANISM.

1,115,002.

Specification of Letters Patent.

Patented Oct. 27, 1914.

Application filed September 12, 1912. Serial No. 719,965.

To all whom it may concern:

Be it known that I, ROBERT MIEHLE, of Chicago, in the county of Cook and State of Illinois, have invented certain new and useful Improvements in Reciprocating-Bed-Driving Mechanism; and I hereby declare that the following is a full, clear, and exact description thereof, reference being had to the accompanying drawings, which form 10 part of this specification.

This invention is a novel means for driving parts of machines with variable power or speed from a uniformly driven part.

The invention particularly relates to that 15 class of machines in which a heavy bed or body is to be reciprocated, as in a printing press wherein the printing surface is carried on a bed having a reciprocating movement under the impression cylinder.

20 The invention has for its principal object to provide a driving mechanism for such a machine that will permit it being operated at a higher rate of speed and produce a larger product than heretofore; and this is 25 accomplished by providing a novel driving mechanism which will transmit the power from a uniformly operating prime mover to the main operative parts of the machine with augmented power at the time when the 30 greatest amount of work is to be performed and with less power as the strain decreases; and when applied to a printing press of the kind mentioned in effect will impart accelerated and retarded movements to the operative parts of the machine at the desired 35 times.

In the example illustrated in the drawings the object is accomplished by means of a main driving gear which may be positioned 40 eccentric to an intermediate driving gear and is connected to rotate the latter and the intermediate driving gear communicates motion and transmits power from the main driving gear to the bed reciprocating mechanism; or when applied to printing presses it may transmit power and communicate motion to both the impression cylinder and the bed. By the said mechanism the whole machine may be slowed down on the last

half stroke of the bed and increased on the 50 first half stroke of the bed.

I will explain the invention in detail in connection with the accompanying drawings which show one specific embodiment thereof and will enable those skilled in the 55 art to understand and use the same; and the essential features of the invention are summarized in the claims.

In said drawings: Figure 1 is a gear side elevation of a printing press partly broken 60 away. Fig. 2 is a rear end elevation of Fig. 1 partly in section. Figs. 3 and 4 are enlarged sectional plan views showing more in detail the construction of the bed motion mechanism. Fig. 5 is a detail sectional elevation 65 of the means for shifting the bed driving gear. Fig. 6 is a detail side view of the supporting frame of the main driving gear. Fig. 7 is a detail top plan view partly in section of the main driving mechanism. 70

In the drawings F designates the main frame of the machine, which, in the example shown, is a flat bed printing press having a reciprocating bed 2 that may be mounted in the usual manner upon suitable supports in 75 the frame; and above this bed is a cylinder 13 the shaft of which is journaled in bearings on the side members 14 and 15 of the frame.

To the bed 2 is secured a rack frame 1 80 carrying upper and lower racks 3 and 4 which are adapted to be alternately meshed with a bed driving gear 5, which is mounted on the inner end of a shaft 6 that is journaled in a suitable bearing 20 in a swinging 85 or rocking frame 20' that is mounted on a shaft 16 supported upon standards 18 and 19 in the main frame. This rocker frame may be moved at the proper times so as to shift gear 5 into position to mesh with rack 90 3 or rack 4, by means of an arm 21, attached to the rocker frame, carrying a stud or roller 22 engaging a cam groove 23 in a cam 24 mounted on a shaft 25 suitably journaled in the frame parallel with the shaft 6 95 (Figs. 4 and 5); which shaft 25 may be driven by means of a gear 27 on its outer end meshing with a pinion 27' on a stud 27';

and said pinion 27' is fast to a pinion 26 meshing with the intermediate driving gear 9. This intermediate driving gear 9 also meshes with a gear 12 on the cylinder shaft. 5 The bed driving gear shaft 6 extends through the rocker frame 21 to the outside of the main frame and has on its outer end a gear 7, preferably of the same size as the gear 5, which meshes with an internal gear 10 8 which is preferably rigidly attached to or formed integral with the gear 9 so that said gears must rotate together. The said gears 8 and 9 are rigidly secured to or mounted on the inner end of a stub shaft 36 extending parallel with shaft 6 but not in axial alignment therewith. The stub shaft 36 is 15 preferably journaled in a bearing 37 mounted upon a lateral auxiliary frame or bracket F' attached to the side of the main frame F. 20 Beside gears 8 and 9 is the main driving gear 44 which, in the example shown, is mounted upon an annular journal 45 formed on, or rigidly secured to, an arm 46 which is pivotally supported at one end on 25 a shaft 10^a that is journaled in bearings in the bracket F' parallel with the shaft 36, and preferably in axial alignment with shaft 27^a. The annular journal 45 on arm 46 is of larger internal diameter than the shaft 36, and surrounds this shaft as indicated in 30 Figs. 1, 2, 6, and 7. Suitable means should be provided for adjusting the annular journal 45, and the gear 44 thereon, eccentrically of the gear 9. As shown bolts 45^a are connected to the annulus 45 and project through 35 slots 45^b in a flange 37^b on the inner end of bearing 17, see Figs. 1, 4 and 7; and thus the free end of the arm 46 can be adjusted relatively to the bearing 37, so as to shift the 40 gear 44 eccentrically of the gear 9. In the normal operative position of parts the gear 44 is adjusted to the position indicated in Figs. 1, 4, 6 and 7, so that it is eccentric to the gear 9. 45 The main driving gear 44 drives the intermediate driving gear 9 by means of lateral interlocking devices therebetween, which preferably consists of a pin or stud 41 rigidly attached to one side of gear 9 and 50 rotatably engaged with a block 42 slidably mounted in a radial slot 43 in the opposed face of the gear 44. This pin and slot connection forms a self-adjusting positive drive between the eccentrically displaced gears 44 and 9, so that when gear 44 is rotated gear 9 55 is caused to rotate therewith. The gear 44 may be driven at a continuous speed by means of a pinion 10 fixed on shaft 10^a; and shaft 10^a may be driven by any suitable 60 motor, not shown.

It will be seen by reference to Figs. 1 and 4 that the main driving gear 44 is slightly eccentric to gears 8 and 9, but as gear 44 rotates it will through the block and pin

42, 41, impart rotary motion to gears 8 and 65 9; but owing to the relative eccentricity of the gears the gears 8 and 9 will not rotate at uniform speed with the gear 44; but instead will rotate more slowly than gear 44 when the pin 41 in its orbital rotation comes nearest 70 to the axis of the gear 44, and will rotate more rapidly than gear 44 when said pin 41 is most distant from the axis of this gear 44. In this way while gear 44 may be rotated at uniform speed gears 8 and 9 will 75 have a variable speed, being actually (although perhaps not perceptibly) accelerated during one half of their rotation and retarded during the second half of their rotation. By reason of this variation in the 80 movement imparted to gears 8 and 9 it follows that the bed driving gear 5 which is operated directly from gear 8 through the gear 7 and shaft 6 will be correspondingly accelerated and retarded during its rotation, 85 and the cylinder 13 will be correspondingly accelerated and retarded by reason of the direct meshing of its gear 12 with the gear 9. It also follows that the cam 24 will be correspondingly accelerated and retarded in its 90 rotation by reason of the fact that it is driven through gears 26, 27' and 27 from the gear 9. By the said means I am enabled to impart to the press bed and to the cylinder a variable speed, from a uniformly driven 95 driving gear; and can impart to the cylinder and to the bed accelerated and retarded movements in absolute harmony with the rack bed motion movement from a uniformly speeded driving gear. 100

As applied to printing presses it is desirable to reduce the speed of or power applied to driving, the bed as it approaches the ends of its strokes. Customarily the bed driving mechanism of all these presses 105 (such as bed driving gear 5 and co-acting rack 3 or 4) impart a uniform speed or movement to the bed from the time the gear meshes with the rack until it goes out of mesh therewith. It is desirable to have the 110 bed driven at uniform speed during the printing and to drive it as rapidly as possible during the major portion of its stroke; it is also desirable to slow down the movement of the bed as it approaches each end 115 of the uniform part of its stroke, and before it is taken under control of the reversing mechanism. It is obvious that if the bed driving gear 5 is driven at a uniform speed there will be no slowing down of the bed 120 until it is taken under control of the reversing mechanism; but by the employment of my present invention (the driving gear 44 being adjusted eccentrically of the intermediate gears 8 and 9) the bed driving gear 125 5 will have a varying speed during each rotation; and the gears can be so adjusted that said gear 5 will be at its lowest speed

when it first runs into mesh with the rack 4 (or 3), and its speed will accelerate during the first half of its revolution and until it reaches the center of the rack, and then its speed will decrease until it reaches the end of the rack. In this invention, notwithstanding that the driving gear 44 is rotated at uniform speed, the bed is accelerated on the first half of the uniform part of each stroke and retarded or decreased on the last half of such part of each stroke. It will also be seen that the cylinder is similarly accelerated and retarded during each rotation thereof, so that the bed and cylinder work in harmony. By thus actuating the bed I am enabled to reciprocate it at greater speed with less jarring and shock than would be possible with a uniformly speeded bed driving gear.

If it should be desired at any time to have the press operate with the ordinary regular uniform motion of the bed, the gear 44 can be readily adjusted into axial alinement with the gear 9; such adjustment might be desirable when printing coated stock with heavy inks; but in order to obtain the benefit of the present invention the gear 44 should be adjusted eccentric to gear 9 as above explained.

The bed may be reversed at the end of its stroke and during the time when gear 5 is run out of mesh with one rack and being shifted into position to mesh with the other rack, by any suitable means, many such being known in the art. In the drawings I have shown a reversing crank 34 fixed to the bed driving gear 5 and provided with a friction roller 35, which operates in slots formed by the gates 28 and 28', and the shoulders 40 and 40'; said gates are moved into and out of the path of the roller 35 by the cams 31, 31', 33 and 33'.

The operation of the gates during the reversal of the bed is briefly as follows: When the press bed is at a stop at the end of its non-printing stroke (Fig. 4) driving gear 5 is disengaged from both racks 3 and 4, and the movement of the press bed is then controlled by the crank 34, working in the slot formed by the shoulder 40' of the rack frame

1 and the working face 39' of the gate 28'. The roller 32' and cam 33 holds the gate 28' closed. When the driving gear 5 is rotated, the press bed and rack frame will move to the left on the printing stroke; the roller 32' will pass over the portion *f* of the cam 33, and roller 30' (on arm 29') pass over the portion *g* of the cam 31', thus opening the gate 28' and releasing the crank 34. At the same time that crank 34 is thus released, driving gear 5 (which has been raised by the movement of the bed motion rocker frame 20) engages with upper rack 3 and drives the press bed during its major part of its stroke.

Near the end of the printing stroke the roller 32 passes over the portion *c* of the cam 33', and roller 30 (on the arm 29) passes over the portion *d* of the cam 31, thus closing the gate 28, and engaging the roller 35 on crank 34 in the slot formed by the working surface 39 (of the gate 28) and the shoulder 40 of the rack frame 1. At the same time that the roller 35 on crank 34 is so engaged, the driving gear 5 is lowered by the movement of the bed motion rocker frame 20, and is thus disengaged from upper rack 3, the press bed being then controlled by the roller 35 in the slot formed between 39 and 40 as above, and coming to a full stop in the position shown in Fig. 3. On the non-printing stroke the operation of the gate 28 is similar to the operation of gate 28' at the beginning of the printing stroke; and the operation of the gate 28' at the end of the non-printing stroke is similar to the operation of the gate 28 at the end of the printing stroke.

While I have shown and described upper and lower racks 3 and 4 alternately meshed by the gear 5 to reciprocate the bed; I do not consider the invention restricted to any particular form of mechanism for transmitting motion from the bed driving gear to the bed, as many equivalent devices are known in the arts that could be used with the gear 5. Nor do I wish to restrict the invention to a rising or falling gear 5; neither do I herein claim the specific construction of devices for reversing the bed at each end of its stroke, many such being known in the art which could be readily substituted therefor. In short my invention is adapted for use with a great variety of forms of bed driving and reversing mechanisms with the resultant advantages above described.

It will be seen that my invention provides means for retarding and accelerating the ordinary means for operating the press bed which embodies customarily means for retarding and accelerating the movement of the bed during the reversal thereof at the ends of its strokes.

What I claim is:

1. In combination, a main driving gear, an intermediate internal driving gear beside and eccentric to the main driving gear, connections between said gears causing them to rotate together, said intermediate gear having a variable speed compared with the speed of the main driving gear; and means for adjusting the relative eccentricities of said gears; with a reciprocating bed, a bed driving gear, and means for operating said bed driving gear from said intermediate gear, whereby the power applied to the bed is correspondingly varied during each of its strokes.

2. In combination, a reciprocatory bed, a

bed driving gear, and means for converting the rotary motion of said gear into a reciprocatory motion of the said bed; with a pinion fixed to the shaft of the bed driving gear, an intermediate gear driving said pinion, a main driving gear beside and eccentric to the intermediate gear, and lateral connections between said gears causing the intermediate gear to rotate with the main driving gear but at variable speed.

3. In a printing press, the combination of a reciprocating bed, a bed driving gear, and means for converting the rotary motion of said gear into reciprocatory motion of the said bed; with a pinion fixed to the shaft of the bed driving gear, an intermediate gear driving said pinion; a main driving gear beside and eccentric to the intermediate gear, means for varying the relative eccentric displacement of said gears, and lateral connections between said gears causing the intermediate gear to rotate with the main driving gear but at variable speed.

4. In a printing press, the combination of a reciprocating bed, a bed driving gear, means for converting the rotary motion of said gear into reciprocatory motion of the said bed, and an intermediate gear driving said bed driving gear; a main driving gear beside and eccentric to the intermediate gear, and lateral connections between said gears causing the intermediate gear to rotate with the main driving gear at variable speed, whereby the speed of the press bed may be alternately accelerated and decreased; with a cylinder coöperating with the bed, and gearing for driving said cylinder from said intermediate gear, whereby the rotary movement of the cylinder is varied in accordance with the variable speed imparted to the bed.

5. In a printing press, the combination of a reciprocating bed, a bed driving gear, and means for converting the rotary motion of said gear into reciprocatory motion of the said bed; a pinion fixed to the shaft of the bed driving gear, an intermediate gear driving said pinion; a main driving gear beside and eccentric to the intermediate gear; lateral connections between said gears causing the intermediate gear to rotate with the main driving gear at variable speed; and means for varying the relative eccentric displacement of said gear whereby the speed of the press bed may be accelerated during the one part of its stroke and decreased during another part of its stroke; with a cylinder coöperating with the bed and gearing for driving said cylinder from said intermediate gear whereby a variable rotary speed is imparted to the cylinder in accordance with the variable speed imparted to the bed.

6. In a printing press, the combination of a reciprocating bed, opposite racks on the bed, a bed driving gear adapted to alternately engage said racks, a rocking support for the gear, a cam for oscillating said support to shift it into engagement with the racks; an intermediate gear operating the bed driving gear; a main driving gear beside and eccentric to the intermediate driving gear, and connections between said gears causing the intermediate driving gear to turn with the main driving gear but at variable speed relative thereto, whereby the motion transmitted to the bed driving gear causes the bed to gradually lessen speed during one portion of its stroke and gradually accelerate speed at another portion of its stroke.

7. In a printing press, the combination of a reciprocating bed, opposite racks on the bed, a bed driving gear adapted to alternately engage said racks, a rocking support for the gear, a cam for oscillating said support to shift it into engagement with the racks, and a pinion on the bed driving gear shaft; an intermediate gear and means for actuating the bed driving gear therefrom; a main driving gear beside and eccentric to the intermediate driving gear; connections between said gears causing the intermediate driving gear to turn with the main driving gear but at variable speed relative thereto, whereby the motion transmitted to the bed driving gear causes the bed to gradually lessen speed during one portion of its stroke and gradually accelerate its speed at another portion of its stroke; with a cylinder and gearing between the intermediate gear and the cylinder shaft whereby the cylinder is caused to turn at a variable speed in accordance with the variation of the speed of the bed driving gear.

8. In a printing press, the combination of a reciprocating bed, a bed driving gear, a pinion on the shaft of the bed driving gear, an internal gear meshing with said pinion, an intermediate driving gear fast to the internal gear, a main driving gear beside and eccentric to the intermediate driving gear, and means for causing the intermediate driving gear to turn with the main driving gear but at a variable speed relative thereto, substantially as described.

9. In a printing press, the combination of a reciprocating bed, a bed driving gear, a pinion on the shaft of the bed driving gear, an internal gear meshing with said pinion, an intermediate driving gear fast to the internal gear, a main driving gear beside and eccentric to the intermediate driving gear, connections causing the intermediate driving gear to turn with the main driving gear but at a variable speed relative thereto, whereby the motion transmitted to the bed

- driving gear causes the bed to gradually lessen speed during one portion of its stroke and gradually accelerate its speed at another portion of its stroke; with a cylinder, 5 and gearing between the intermediate gear and the cylinder shaft, whereby the cylinder is caused to turn at variable speed in accordance with the variation of the speed in the bed driving gear.
- 10 10. In a printing press, the combination of a reciprocating bed, a cylinder co-acting therewith, opposite racks on the bed, a bed driving gear adapted to alternately engage said racks, a rocking support for the gear, 15 a cam for oscillating said support to shift it into engagement with the racks; a pinion on the shaft of the bed driving gear, an internal gear meshing with said pinion, an intermediate driving gear rotatable with 20 said internal gear, a main driving gear beside and eccentric to the intermediate driving gear, pin and slot connections between the intermediate driving gear and the main driving gear whereby the rotary motion of 25 the intermediate gear varies from that of the main driving gear; gearing between the intermediate gear and the cylinder shaft, and gearing for operating the cam actuating shaft.
- 30 11. In combination, a revolute impression-cylinder, means to revolve said cylinder, a reciprocating bed, means to reciprocate the bed, means for retarding the movement of the bed as it approaches each end 35 of the stroke and accelerating its initial movement in the opposite direction, and supplemental means to cause an equal acceleration of the movements of the cylinder and bed during the first portion of the bed 40 stroke and to retard their movements equally during the latter portion of the bed stroke, substantially as described.
12. In combination, a revolute impression-cylinder, means to revolve said cylinder, a reciprocating bed, means for reciprocating the bed, means for retarding the movement of the bed as it approaches each 45 end of its stroke and accelerating its initial movement in the opposite direction, and supplemental means to accelerate equally 50 the movements of the cylinder and bed during the first portion of the bed stroke and to retard equally their movements during the latter portion of the bed stroke, substantially as described.
- 55 13. In combination, a revolute impression-cylinder, means to revolve said cylinder at a substantially uniform speed, a reciprocating bed, means for reciprocating the bed at a substantially uniform speed, means for retarding the movement of the bed as it approaches each end of the stroke 60 and accelerating its initial movement in the opposite direction, and supplemental means
- to accelerate the movements of the cylinder and bed equally during the first portion of the bed stroke and to retard their movements equally during the latter portion of the bed stroke, substantially as described. 65
14. In combination, a reciprocating member, a rotatable gear, and connections between said gear and said member for reciprocating the latter; with an intermediate driving gear meshing with the rotatable gear, a main driving gear beside and adjustable radially of the intermediate gear, and lateral connections between the latter gears whereby power applied to the main driving gear is variably transmitted to the rotatable gear. 70
- 75 15. In combination, a reciprocating bed, a rotatable gear, and means actuated by said gear for reciprocating the bed; with a main driving gear, an intermediate gear meshing with the rotatable gear, and arranged beside the main driving gear, said main driving gear being adjustable radially with respect to said intermediate gear, and lateral connections between the said intermediate and driving gears whereby the intermediate gear is caused to turn with the main driving gear in any adjusted position of the latter. 80
- 85 16. In combination with a reciprocating member, a rotatable gear, means operated by said gear for reciprocating the member, and an internal gear engaging said rotatable gear; with a driving gear located eccentrically to the internal gear, and interlocking connections between said internal 90 and driving gears whereby the power applied to the member is alternately increased and diminished during each of its strokes. 95
- 100 17. In combination, a reciprocating member, a rotatable gear, and means operated by said gear for reciprocating the member; with an internal gear engaging said rotatable gear, a driving gear located eccentrically to the internal gear, and lateral connections between the internal and driving 105 gears whereby the latter gear causes the rotation of the rotatable gear at a varying speed and the speed of the member is alternately increased and diminished during each of its strokes. 110
- 110 18. In combination, a reciprocating bed, a bed driving gear, and means actuated by said gear for reciprocating the bed; with an internal gear, a gear connected with the bed driving gear and meshing said internal gear, a main driving gear beside but eccentric to the internal gear; and lateral connections between the said internal and main driving gears, whereby the bed driving gear is caused to operate the bed at variable 115 speed. 120
- 125 19. In combination, a main driving gear, an intermediate driving gear beside and ec-

centric to the main driving gear, a pin and slot connection between said gears causing them to rotate together, the intermediate gear having a variable speed as compared 5 with the speed of the main driving gear; and means for adjusting the relative eccentricities of said gears; with a reciprocating member, a gear meshing with said intermediate gear, and means for operating said 10 member from the latter gear whereby the

power applied to said member is variable during each of its strokes.

In testimony that I claim the foregoing as my own, I affix my signature in presence of two witnesses.

ROBERT MIEHLE.
